UNITED STATES PATENT OFFICE.

CAIUS C. BRAGG, OF AVONDALE, OHIO.

CAMERA.

SPECIFICATION forming part of Letters Patent No. 339,736, dated April 13, 1886.

Application filed July 2, 1885. Serial No. 170,472. (No model.)

To all whom it may concern:

Be it known that I, CAIUS C. BRAGG, a citizen of the United States, residing at Avondale, in the county of Hamilton and State of Ohio, have invented certain new and useful Improvements in Cameras, of which the following is a specification, reference being had therein to the accompanying drawings.

This invention relates to those cameras which are employed for taking photographic and other "sun pictures;" and the first part of my improvements consists in providing such instruments with an adjustable secondary or auxiliary lens that is used for focusing the main lens. This secondary lens, which is usually less in diameter and shorter in focus than the main lens, is adapted to throw its picture on a ground glass fitted within the camera, and thereby indicate when the main lens is in focus, it being understood that the two lenses bear a certain known proportion to each other, as hereinafter more fully described.

The second part of my improvements comprises a novel combination of devices whereby the two lenses are simultaneously shifted or adjusted in exact proportion to their relative focusing power, as hereinafter more fully described.

The third part of my improvements consists in providing a camera with a flexible shutter capable of being uncoiled from one drum and wound upon another, so as to give either an "instantaneous" or "time" exposure, as may be desired. This flexible shutter has an opening in it which allows the light from the main lens to pass through and act on the plate or other sensitized medium fitted within the camera, as hereinafter more fully described.

The fourth part of my improvements comprises a novel combination of devices, whereby the various movements of the flexible shutter are readily effected by the operator, as hereinafter more fully described.

The fifth part of my improvements comprises a novel combination of devices, whereby a single clutch-shaft is caused to perform the twofold purpose of adjusting the main and auxiliary lenses and operating the flexible shutter, as hereinafter more fully described.

In the annexed drawings, Figure 1 is a front

elevation of my improved camera. Fig. 2 is a plan of a portion of the top of the same. Fig. 3 is a view of the camera after the front end has been removed therefrom. Fig. 4 is a horizontal section of the instrument, said section being taken in the plane of the lever H. Fig. 5 is a vertical section of the camera taken in the plane of the auxiliary lens C. Fig. 6 is an enlarged plan of the clutch-shaft that operates the lenses and the flexible shutter. Fig. 7 is a transverse section of said shaft. Fig. 8 is a modification of the rack and pinion that operate the lenses of the instrument. Figs. 9 and 10 are modifications of the devices for communicating motion from the main lens to the lever that shifts or adjusts the secondary lens. Fig. 11 is a horizontal section of a portion of the camera, said section being taken in the plane of the main lens B. Fig. 12 is a rear elevation of the flexible shutter, said device being shown coiled upon the solid drum, so as to cut off the light from the main lens. Fig. 13 is a similar elevation, but showing the shutter partially coiled around the hollow drum or cylinder, so as to admit the light from the main lens. Fig. 14 is a horizontal section of the shutter uncoiled from the solid drum. Figs. 15, 16, and 17 are enlarged plans, showing in different positions the pawls that arrest the revolution of the solid drum. Fig. 18 is a plan of the stop-lever of said drum. Fig. 19 is an enlarged axial section of the hollow drum or cylinder. Fig. 20 is a modification of the device that operates said cylinder. Fig. 21 includes two elevations of the cam-disk of the solid drum. Fig. 22 includes a longitudinal section and plan of the preferred arrangement of devices wherewith the shaft of the hollow drum is coupled to the supporting-frame or housing.

The box or camera A, which may be of any suitable size, shape, and material, has fitted in its front an end piece, A', pierced at *a'a* to admit light to the main lens B and secondary or auxiliary lens C, the former being mounted in a customary telescopic tube, *b' b*, of which tube the adjustable section *b* has an ordinary rack, *b''*, applied thereto. This rack engages with a pinion, *d*, on one end of a shaft, D, whose other end is confined within a clutch-shaft, E, being coupled thereto by a transverse pin, *d'*, that

traverses the longitudinal slot *e* of said clutch-shaft, as seen in Figs. 6 and 7. Furthermore, this clutch-shaft carries a disk, *F*, slotted at *f*, to permit free passage of the pin *d'*, the extreme outer end of said shaft being provided with a milled head or knob, *e'*, wherewith it is readily operated. The adjustable section *b*, that carries the main lens *B*, has a shade, *G*, from which depends a pin, *g*, traversing the forked end *h* of a lever, *H*, the latter being fulcrumed to the camera at *h'*.

h'' is a longitudinal slot in said lever to admit a pin, *I*, that depends from an upper plate, *i*, and passes through a hole in a lower plate, *i'*, which latter is securely soldered to the lever *H*. The upper plate, *i*, is soldered to a shank, *j*, of the shiftable tube *J*, that carries the auxiliary lens *C*, said tube *J* being adjustable within a fixed tube, *c*, applied to the chamber *K*. The shank *j* traverses a slot, *c'*, in the lower side of fixed tube *c*, and also passes through a slot, *k*, in the bottom of chamber *K*, the latter being furnished with a mirror, *k'*, a ground glass, *k''*, and a door or lid, *k'''*, capable of being readily opened and closed.

The object of soldering the two plates *i i'* to the shank *j* and lever *H*, respectively, is to afford an extended bearing for said shank, and thereby cause it to move steadily and without any material tremor while traveling along the slots *c' k*, which latter may be flanked with a pair of guide-plates, *l l'*, as more clearly seen in Fig. 4.

Completely dividing the camera, and placed at a suitable distance in rear of the front end therof, is a partition, *L*, having a central circular opening, *l''*, which is in line with the fixed section *b'* of the main-lens tube, as more clearly seen in Figs. 11, 13, and 14. The rear side of this partition has secured to it a pair of parallel plates, *M M'*, that support a fixed shaft, *m*, and a revolving shaft, *m'*, the former of which occupies an axial position within a hollow drum or cylinder, *N*, which must be so arranged as to automatically coil the flexible shutter thereon. The preferred method of accomplishing this result is seen in Fig. 19, where a coiled spring, *n*, is wound round the shaft *m*, and has one end attached thereto, while the opposite end of said spring is secured to the cylinder *N*. Fastened to the other shaft, *m'*, so as to revolve therewith, is a solid drum, *N'*, to which is secured one end of a flexible shutter, *O*, the other end thereof being attached to the cylinder *N*. This shutter may be made of any material capable of being readily wound around these drums *N N'*, and is provided with an opening, *o*, that exposes the opening *l'* of the partition *L*, when said shutter is properly shifted, as seen in Fig. 13.

Securely fastened to the lower end of shaft *m'* is a grooved wheel, *P*, to which is attached one end of a cord or thong or light chain, *p*, that is carried through the partition *L*, and thence out at the side of the camera, the exposed extremity of said cord being provided with a convenient pull, *p'*. (Seen in Figs. 1,

2, and 3.) Projecting from the periphery of this wheel is a lug, *p''*, adapted to strike against the free end of a stop-lever, *Q*, the latter being hinged to the plate *M'* at *q*, and having a stump, *q'*, that traverses the slot *m''* of said plate. The upper end of shaft *m* has immovably secured to it a cam-shaped disk, *R*, provided with a shoulder, *r*, extending completely across its face, and a tooth, *r'*, that extends only about half-way across said face, the peculiar arrangement of these teeth being more clearly seen in Fig. 21.

Adapted to engage either with the shoulder *r* or with the tooth *r'* of the cam-disk *R* is the lowermost pawl, *S*; of a pair of pawls, *S S'*, hung upon a common pivot, *T*, which pivot is tapped into the upper plate, *M*. The upper pawl, *S'*, however, is adapted to engage only with the shoulder *r*, and is provided with a pin, *s*, that enters a slot, *s*, of the lower pawl, and thereby communicates motion to the latter.

t is a spring that maintains the lower pawl, *S*, in its normal position, and *t'* is a stop that limits the opening swing of the upper pawl, *S'*. Attached to the lower pawl, *S*, is one end of a cord, thong, or light chain, *U*, which, after being passed through the partition *L*, has its other extremity fastened to the upper end of a lever, *V*, the latter being pivoted to said partition, as seen at *v* in Fig. 3. Furthermore, the lower end of this lever is forked at *v'*, to admit the edge of disk *F*, as seen in Figs. 4 and 7.

Attached to the upper pawl, *S'*, is one end of a cord or thong or light chain, *U'*, which is passed through the partition *L*, thence over a sheave, *u*, and is finally attached to the upper end of the lever *V*.

The preferred method of fitting the fixed shaft *m* within the plate *M* is seen in Fig. 22, where said shaft is represented as provided with one or more lateral pins or other projections, *w*, adapted to enter slots *W* in said plate.

X is a washer interposed between said plate and the head of a screw, *Y*, the latter being tapped in the end of shaft *m*, and the extremity of the shaft being nicked or grooved at *Z*, to admit a screw-driver or other similar implement. It will be seen that by disengaging the screw *Y* the shaft *m* can be shifted longitudinally, so as to free the pins *w* from the slots *W*, and a screw-driver being now inserted in the nick *Z*, said shaft can be turned either to the right or left until the desired tension has been imparted to the spring *n*, (seen in Fig. 19,) after which act the shaft is shifted back to its normal position and retained in place by the screw, the pins *w* serving to prevent said shaft being turned by the tension of the spring.

The method of operating my improved camera is as follows: I will suppose that the spring *n* has been allowed to exercise its force and has wound the flexible shutter *O* around the cylinder *N*, thereby uncoiling said shutter

from the drum N' , as represented in Fig. 14, and winding the cord p around the grooved wheel P , as seen in Fig. 13. This act causes the lug p' of said wheel to strike against the under edge of lever Q and force the latter aside until said lever assumes the position indicated by the dotted lines in Fig. 18. The stump q' is thus brought in contact with the appropriate end of the slot m' , thereby causing the device Q to act as a stop-lever, that arrests the rotation of the drum N' at the proper position. Cord p is now pulled to uncoil it from the grooved wheel P , which act uncoils the shutter from the cylinder N and winds it around the drum N' , as seen in Fig. 11, thereby imparting considerable tension to the spring n , confined within said cylinder. Furthermore, when the drum N' is thus turned, the lug p' of the wheel P strikes against the lever Q , as shown by the heavy lines in Fig. 18, thereby bringing the stump q' in contact with the other end of slot m' and preventing said drum being turned too far. A sensitized plate is then inserted in the rear portion of the camera, and the apparatus is at once ready for immediate use, no light being now admitted to act on said plate, because the imperforate portion of the flexible shutter is closing the opening l'' in the partition L . When the operator arrives at a suitable place, presuming he is engaged in taking outdoor-pictures, he opens the door k'' and turns the knob d' , so as to either advance or retract the auxiliary lens C , until a sharp and well-defined picture is thrown upon the ground glass k'' . The moment this is done he knows the main lens B is also in proper focus, because the two lenses are so coupled together as to render it impossible to focus one without at the same time focusing the other. Having thus obtained the proper focus of the main lens without admitting a ray of light into the camera, the next proceeding will be determined by the kind of exposure required—that is to say, whether it shall be an instantaneous or time exposure, and, presuming the latter has been determined on, the operation will be as follows: Knob e' is pulled so as to advance the clutch-shaft E and cause its disk F to swing the lower end of lever V in the direction indicated by the double-headed arrow in Fig. 3, which movement of shaft E does not in the least interfere with the shaft D and pinion d , because the former shaft, E , slides freely along the latter shaft, D ; but this movement of the clutch-shaft pulls the cord U' , that connects with the upper pawl, S' , and the latter communicates its motion to the lower pawl, S , by means of the pin s' coming in contact with the appropriate end of slot s . Consequently these two pawls move together, and are simultaneously freed from the extended shoulder r of cam-disk R , with which they were automatically engaged by the stress of spring t the instant the flexible shutter was wound around the drum N' . Said drum being thus unlocked, there is now nothing to prevent the coiled

spring n exerting its force against the cylinder N , which latter is accordingly turned so as to wind the shutter O thereon. It is evident this coiling of the shutter on the cylinder must cause a corresponding unwinding of the drum N' , and as soon as the latter has made a half-revolution it is arrested by the lower pawl, S , engaging with the tooth r' ; but the other pawl, S' , is not now thrown in lock with the cam-disk R , because said tooth extends only across a portion of the face of said disk. This half-revolution of the drum N' brings the opening o of the shutter in line with the opening l'' of the partition L , as seen in Fig. 13, and thereby affords the desired "exposure." After the proper time has elapsed the operator presses against the knob e' , thereby causing the disk F to swing the lower end of lever V in the direction of the single-headed arrow, (seen in Fig. 3,) and pulling the cord U , so as to release the lower pawl, S , from the tooth r' . This act leaves the spring n again at liberty to exercise its force, and causes a further revolution of cylinder N until the lug p' again comes in contact with the stop-lever Q and both pawls engage with the shoulder r . The shutter is now coiled around the cylinder N and the light is completely cut off from the main lens, as seen in Fig. 14, and the above-described operations are repeated as often as it is desired to make a "time exposure;" but when an "instantaneous exposure" is desired the knob e' is simply pressed so as to disengage both of the pawls from the cam-disk and allow the drum N' to make one complete revolution at the very start, no stoppage of said drum being allowed at a half-turn of the same, because the pressure against said knob is maintained until the lug p' comes in contact with the stop-lever Q . For this reason the lower pawl, S , does not now engage with the tooth r' at the half-turn of the drum N' , and as the shutter is thus uninterruptedly coiled on the cylinder N the passage of the opening o across the hole l'' of the partition L occupies but the very shortest interval of time. Although this admission of light through the opening l'' and the cutting off of the rays occupies but a moment, yet it is sufficient to produce what is known as an "instantaneous exposure" that affords a sharp and well-defined picture on a properly-sensitized plate.

From the above description it is apparent that the arrangement of pinion-shaft $D d d'$ and clutch-shaft $E e e' F$ is such as to enable said shafts to perform the twofold purpose of adjusting the main and secondary lenses and also of operating the automatic shutter, thereby reducing the complexity of the instrument and allowing the camera to be operated with the greatest convenience.

Instead of employing the lever H for communicating motion from the main to the secondary lens, the shaft D may have two pinions, $D' D''$, of unequal diameters, as seen in Fig. 8, which pinions should engage respect-

ively with the racks B' C' of the primary and secondary lenses B C. The diameters of these pinions D' D'' must be in exact proportion to the power of the two lenses B C, in order that 5 the focusing of the smaller one will insure the proper adjustment of the larger lens; but in Fig. 9 the shade G, is shown as capable of being turned either to the right or to the left, so as to cause the pin g to advance toward or 10 recede from the forked end h of the lever H and thereby regulate the stroke of the latter.

In Fig. 10 is shown an arrangement of devices whereby the stroke of the lever can be regulated with the utmost nicety, so as to compensate for very slight differences in the focusing power of the two lenses B and C. Here 15 the pin g is either advanced or retracted by means of a screw, g', which latter turns within a bearing, G', secured to the tube that carries the main lens.

In Fig. 20 is shown a substitute for the coiled spring n, an elastic thong, n', being provided, one end of which is attached to a wheel, n'', on the end of the shaft m, while the other end 25 of said thong is fastened to the plate M'. This construction would necessitate the cylinder N turning with said shaft.

The provision of the cam-disk R r r' causes 30 the pivoted pawls S S' to act without producing any serious jar or concussion of the camera.

I am aware it is not new to provide a camera with a secondary or "finding" lens, which is fixed within the apparatus, and is incapable of being adjusted to designate when the main 35 lens is exactly in focus. Such a fixed finding-lens is therefore expressly disclaimed as constituting any part of my invention.

I claim as my invention—

1. The combination, in a camera, of a pair 40 of dissimilar lenses coupled together for simultaneous adjustment, substantially as herein described.

2. The combination, in a camera, of a secondary lens adjusted by a lever coupled to the 45 main lens, the latter being operated by a rack and pinion, substantially as herein described.

3. The combination, in a camera, of a secondary lens adjusted by a lever coupled to the main lens, the latter being operated by a 50 rack and pinion actuated by a shaft that controls the shutter of the instrument, substantially as herein described.

4. The combination, in a camera, of a secondary lens adjusted by a lever coupled to the 55 main lens, the latter being operated by a rack and pinion actuated by a shaft that controls a shutter capable of affording either an instantaneous or time exposure, substantially as herein described.

6. The combination, in a camera, of the adjustable main lens B b, adjustable secondary lens C J, pin g, pivoted lever H h h', and shank j, for the purpose described.

65 6. The combination, in a camera, of the adjustable main lens B b, adjustable secondary lens C J, pin g, pivoted lever H h h', shank j,

pinion-shaft D d d', and clutch-shaft E e, which latter carries a disk, F, for operating the shutter of the instrument in the manner described.

7. The combination, in a camera, of a flexible shutter having a suitable opening and capable of being uncoiled from one drum and wound around another drum, for the purpose of affording either a time or instantaneous exposure, said drums being journaled within the camera and one of them being provided with a pair of stops that engage with locking-pawls, the latter being coupled to a swinging lever actuated by an external pull, as e', in order that said inclosed shutter may be operated without opening the camera, substantially as herein described. 7c

8. The combination, in a camera, of a flexible shutter having a suitable opening and capable of being uncoiled from one drum and automatically wound around another drum, for the purpose of affording either a time or instantaneous exposure, said drums being journaled within the camera and one of them being provided with a pair of stops that engage with locking-pawls, the latter being coupled to a swinging lever actuated by an external pull, as e', in order that said inclosed shutter may be operated without opening the camera, substantially as herein described. 80

9. The combination, in a camera, of a flexible shutter having a suitable opening and capable of being uncoiled from one drum and automatically wound around another drum, for the purpose of affording either a time or instantaneous exposure, said drums being journaled within the camera and one of them having a spring coiled therein, while the other drum is provided with a pair of stops 90 that engage with locking-pawls, the latter being coupled to a swinging lever actuated by an external pull, as e', in order that said inclosed shutter may be operated without opening the camera, substantially as herein described. 100

10. The combination, in a camera, of the flexible shutter O o, having its opposite ends secured to the cylinder N and drum N', said cylinder being operated by the spring n, coiled within it, and the drum N' being provided 115 with cord p, grooved pulley P, cam-wheel R, stops r r', pivoted pawls S s S' s', spring t, cords U U' u, and swinging lever V, for coiling said shutter thereon, for locking the drum, and for liberating the latter, so as to afford either an instantaneous or time exposure, as herein described. 110

11. In combination with the flexible shutter O o, attached to the spring-cylinder N n and drum N', in the manner herein described, 125 the shouldered and toothed cam-disk R r r', pivoted pawls S S' T, pin s', slot s, spring t, stop t', and devices that operate said pawls, for the purpose stated.

12. In combination with the flexible shutter O o, attached to the spring-cylinder N n and drum N', in the manner herein described,

the lug p'' , pivoted stop-lever Q q q' , and slot m' , for the purpose stated.

13. In combination with the pivoted pawls S s S' s' T , arranged to operate with the shou-
dered and toothed cam-disk R r r' , in the
manner described, the cords U U' , and piv-
oted lever V v , the latter being provided with
a fork, v' , that admits the disk F of the recip-
rocating shaft E , for the purpose stated.

14. The combination, in a camera, of spring-
cylinder N n , drum N' , flexible shutter O o ,

grooved wheel P , and cord p , which cord is
wound around said wheel when said shutter
is uncoiled from said drum N' , as herein de-
scribed.

15

In testimony whereof I affix my signature in
presence of two witnesses.
